F. A. FULLER.
BAG FASTENER.
APPLICATION FILED MAR. 6, 1917.

1,247,106.

Patented Nov. 20, 1917.

By his Attorney
Inventor
Frank A. Fuller
Frederick C. Fischer.

UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,247,106.

Specification of Letters Patent. Patented Nov. 20, 1917.

Application filed March 6, 1917. Serial No. 152,461.

To all whom it may concern:

Be it known that I, FRANZ A. FULLER, a citizen of the United States, residing in the city of Newark, in the county of Essex and

5 State of New Jersey, have invented certain new and useful Improvements in Bag-Fasteners, of which the following is a full, clear, and exact description, such as will enable others skilled in the art to which it
10 pertains to make, construct, and use the same, reference being had to the accompanying drawings, and to numerals of reference marked thereon, forming a part of this specification.
15 This invention relates to certain improvements in fasteners, and particularly to fasteners for satchels, bags, pocket-books, and the like, and has for its object, the arrangement of an improved structure, designed to
20 co-act with the ordinary fastener of a satchel or the like, for preventing an accidental loosening or unfastening of the same, and to facilitate the opening of the primary fastener, namely, the lift lock.
25 In its preferred embodiment, my improved device consists of a spring-actuated fastener, of the lift-lock type, secured to one of the frame members, and having holding engagement with the other frame member
30 for holding said frame members together, and a locking element pivotally secured to said spring-actuated fastener for additionally holding said members together, the said locking element in general appearance re-
35 sembling what is known as a pull-piece, so that when the same is in locked position or in engagement with the knobs or buttons on the frame members, it serves the purpose of additionally holding said members together,
40 at the same time holding the spring-actuated fastener in its locked position, and which, when disengaged, serves as a pull-piece for releasing the said spring-actuated fastener from its locked position and sepa-
45 rating the bag frame members.

Describing the invention in detail, reference is had to the accompanying drawings forming a part of this specification, wherein, like numerals of reference indicate corresponding parts throughout the several views of the drawings, and in which

50 Figure 1 represents a front elevation of a bag frame having applied thereto my improved fastener.

55 Figs. 2 and 3 represent respectively, a side elevation and a plan view of the same.

Fig. 4 represents on an enlarged scale, a fragmentary sectional view taken on line $\alpha-\alpha$ of Fig. 3, looking in the direction indicated by the arrows. 60

Fig. 5 represents on an enlarged scale, a fragmentary sectional view taken on line $\alpha-\alpha$ of Fig. 1, looking in the direction indicated by the arrows.

Fig. 6 represents a front elevation of a 65 modified form of fastener, as applied to a section of a bag frame.

Figs. 7 and 8 represent end views thereof, the fastener being shown in a tilted position in Fig. 8, preparatory to separating the 70 frame sections; and

Fig. 9 represents a fragmentary sectional detailed view of the fastener.

Referring now to the drawings, 1 and 2 represent a pair of frame sections, which are 75 pivotally connected at their end portions in the usual well-known manner. One of the said frame sections, as 2, is provided in its upper surface with a suitably arranged opening for the reception of an extension 80 3 formed on the spring-actuated catch member, to be presently described, and the other frame section, as 1, is provided with a suitable nosing or projection 4, or any other suitable means may be provided, designed 85 to be brought into holding engagement with a suitable recess or other means formed in the under side of the catch member to firmly 90 secure the bag frame members or sections in locked position. 90

The catch member, which may be of any desired form or configuration, consists preferably of the cap 5, provided with an integral downwardly projecting spring holding member 3 at its rear end, for the reception of a suitable torsion-spring 6, said end passing through the spring holding member 3, and the other end of which is secured in the frame section 2 in any well-known manner. 95

At the rear end of the catch member, a tubular, outwardly-extending bearing 7 is integrally formed with said catch member, to receive one end of the locking element 8. A pair of knobs or buttons 9 are fastened to 105 the frame members 1, and which are designed to have locking engagement with said element 8 when the parts are as shown in Figs. 1 to 5 of the drawings.

The locking element 8 is pivotally connected to the tubular bearing 7, and is preferably made from a single piece of suitable 110

material, formed with a central opening 10, from which extend curved engaging portions or recesses 11, designed to pass over the buttons or knobs 9, and to have locking engagement therewith. The other end of the locking element is preferably brought downwardly in close proximity to the frame member 1 and outwardly to provide a convenient finger or pull piece 14, thereby providing convenient means for manipulating the locking element, in order to disengage the same from the buttons or studs 9, and to further provide convenient means for manipulating the catch member, in order to disengage the same from the nose or locking projection 4 of the frame member 1, as clearly illustrated in Fig. 8 of the drawings.

In the modified form illustrated in Figs. 6 to 9 of the drawings, the locking element 12 differs somewhat from the locking element 8, in that it is not provided with a central opening 10, to expose the cap of the catch member, or the buttons or studs 9, but is shown as provided with a casing 13, said casing adapted to entirely inclose the catch member and buttons or knobs 9, the sides 15 of the said casing 13 engaging with knobs or buttons 9 to have locking engagement therewith, in somewhat the same manner as the engaging portions or recesses 11 of the locking element 8 have locking engagement with the knobs 9.

It will thus be seen that with this device, a most novel lock is obtained. The fact of the locking element being pivotally secured in a bearing 7 formed on the catch member and further having locking engagement with the knobs or buttons 9 on the frame member 1, makes the manipulation of the lock simple, and then when the locking element 8, by means of the pull piece 14, is thrown back or out of engagement with the buttons or knobs 9, the frame members are yet held by the catch member and the nosing, until further pressure is brought to bear upon the locking element, whereby the catch member is lifted out of locking engagement with the nosing.

While I have shown my preferred forms, it will be understood that the invention is not limited to the exact embodiment shown, but may be modified in various ways in the scope of the accompanying claims.

Having thus described my invention, what I desire to claim and secure by Letters Patent is:—

1. In combination two members movable relatively to each other, a spring-actuated fastener secured to one of said members

holding said frame members together, the other frame member being provided with a pair of studs on the top thereof, said fastener being provided with an integral extension forming a bearing, a locking element, one end of which is pivotally secured in said bearing, the central portion being provided with stud-engaging means designed to receive and have holding engagement with the said studs on said frame member for additionally holding said frame members together and independently operated from said fastener.

2. In combination two members movable relatively to each other, a spring-actuated fastener secured to one of said members holding said frame members together, the other frame member being provided with a pair of studs on the top thereof, said fastener being provided with an integral extension forming a bearing, a locking element, one end of which is pivotally secured to said bearing, said locking element overlying the tops of the frame section and provided with engaging means designed to have holding engagement with the studs on one of said frame members for additionally holding said frame members together, the other end of said locking member terminating in a pull piece and lying adjacent to the outside face of one of the frame members.

3. In combination two members movable relatively to each other, a spring-actuated fastener secured to one of said members holding said frame members together, the other frame member being provided with holding means on the top thereof, said fastener being provided with a bearing, a locking element, one end of which is pivotally secured in said bearing and overlying said frame members and provided with a central opening through which the fastener passes and by means of which it is exposed, said central opening being provided with diametrically-alined curved engaging portions or recesses, designed to pass over and have locking engagement with the said holding means on said frame member, the other end of said locking element lying adjacent to the outside face of one of the frame members.

This specification signed and witnessed this 28th day of February, 1917.

FRANZ A. FULLER.
